UNITED STATES PATENT OFFICE.

MONROE KOHN, OF CHICAGO, ILLINOIS.

DISPLAY APPARATUS.

1,112,917.

Specification of Letters Patent.

Patented Oct. 6, 1914.

Application filed July 5, 1911. Serial No. 636,935.

To all whom it may concern:

Be it known that I, MONROE KOHN, a citizen of the United States, residing at Chicago, county of Cook, State of Illinois, have 5 invented a certain new and useful Improvement in Display Apparatus, and declare the following to be a full, clear, and exact description of the same, such as will enable others skilled in the art to which it pertains 10 to make and use the same, reference being had to the accompanying drawings, which form a part of this specification.

My invention has for its object to produce a simple and novel apparatus in which 15 a series of trays may be disposed in step-like formation within a suitable case, be easily and quickly removed and replaced, and be capable of being handled as a single flat tray when removed from the case.

20 The various features of novelty whereby my invention is characterized will hereinafter be pointed out with particularity in the claims; but, for a full understanding of my invention and of its object and advantages, reference may be had to the following 25 detailed description taken in connection with the accompanying drawings, wherein:

Figure 1 is a perspective view of an assembled apparatus arranged in accordance 30 with a preferred form of my invention; Fig. 2 is an end view of the apparatus, showing in dotted lines the door of the casing opened and the trays in position to be removed; and Fig. 3 is an end view of the 35 trays, showing the manner of handling them when removed from the case.

Referring to the drawings, 1 represents a suitably constructed case, preferably of glass for the purpose of exposing to view objects 40 positioned within the case. One side of the case, preferably the back, is made in the form of a door 2 which is hinged at its lower edge as indicated at 3.

4, 5 and 6 represent a series of individual trays approximately as long as the case and having a combined width approximately equal to the depth or width of the case. The trays are connected together in any suitable manner so as to permit them to 45 be moved relatively to each other, making it possible to bring them either into a step formation or into a formation wherein the several trays lie in substantially the same plane. In the arrangement shown, corresponding ends of the trays are connected

together by two parallel bars, there being two of these bars at each end of the trays as indicated at 7 and 8. Each of the bars is pivotally connected or journaled to each of the trays, the pivots or journals being indicated at 9. The pivotal connections of the bars are so arranged that any four of them at either end of two adjacent trays form the corners of a parallelogram. The parts are so arranged that the trays will fit nicely into the case when the rear tray is lifted so as to bring it near the top of the case. When not otherwise supported the trays tend to drop into a single plane so as to permit all of them to rest upon a flat surface. The trays 60 are held in their step-like formation by means of a door which, when closed, bears against the back of the uppermost tray and prevents it from swinging out, the lowermost tray bearing against the front wall of 65 the case. Consequently, when the door is opened, there is nothing to support the trays in their step-like formation and the upper ones descend with the door until they lie flat.

It is often desirable to remove the trays so as to permit a closer inspection to be made of their contents than can be had while the trays are in the case. I therefore provide means for facilitating the removal and the 70 handling of the trays, and for preventing the trays from being placed in the case in such a way that they are apt to become jammed when the door is closed. For the purpose of attaining some of these ends of my 75 invention I provide the rearmost tray, 6, with pins 10 projecting from the ends thereof, and on the door I provide stop members 11 which are adapted to lie below the pins when the trays are assembled in the case and 80 the door is closed, and to engage with the pins as the door is opened and partially withdraw the trays from the case. When 85 the trays are again inserted into the case, after having been removed therefrom, they 90 are set upon the door with the pins 10 just outside of the stops 11 as indicated in dotted lines in Fig. 2; the stops thus limiting the 95 entrance of the trays into the casing before the door is closed. Then, when the door is 100 raised for the purpose of closing the same, the innermost tray slides along the bottom of the case or across suitable rails 12 secured to the bottom while the outermost tray rises 105 to the door and is retarded in its inward 110

movements by the stops which engage with the pins 10. In the preferred arrangement the stops are in the form of hooks which have their open sides directed toward the 5 upper edge of the door.

For the purpose of permitting the several trays to be handled in the same way as if they were a single rigid tray, I secure to the underside of the middle tray a member 13 10 which extends laterally beneath the tray 6. The member 13 may take various forms and extend for any desired distance lengthwise of the trays, it being essential only that it lie in such a position when the trays occupy 15 their plane formation, that it will be engaged by hand grasping the tray 6 so as to be held against the underside of that tray. This of course locks the trays 5 and 6 together and also holds the tray 4 and such 20 other trays as there may be in the series against movement. In the arrangement shown the member 13 is in the form of a shelf at the center of the trays but, as heretofore stated, it may take other forms than 25 this.

While I have illustrated and described only a single preferred form of my invention, I do not desire to be limited to the particular structural details thus illustrated and 30 described; but intend to cover all forms and arrangements which fall within the terms

employed in the definitions of my invention constituting the appended claims.

I claim:

1. In a display apparatus, a show case, a door hinged at the bottom on one side of the case, a plurality of trays movably connected together and forming a series of steps extending downwardly from the side having the door to the opposite side, pins projecting from the ends of the uppermost tray, and hooks carried by the door in positions to engage with said pins when the door is opened, the open sides of the hooks being directed 40 toward the door.

2. In combination, a series of trays, connecting means for the trays arranged to permit them to be adjusted from a step formation to a formation in which the trays lie in a single plane, and a number secured to the underside of one of the intermediate trays and projecting under one of the outer trays in a position to be grasped by a hand holding the latter tray when the trays are in the 50 plane formation.

In testimony whereof, I sign this specification in the presence of two witnesses.

MONROE KOHN.
